(57) **CLAIM**

The ornamental design for a bracelet fastening tool, as shown and described.

DESCRIPTION

FIG. 1 is an isometric view of the bracelet fastening tool, as viewed from the rear towards the front;

FIG. 2 is an isometric view of the bracelet fastening tool, as viewed from the front towards the rear;

FIG. 3 is a side elevational view, of the bracelet fastening tool, as viewed from the bottom;

FIG. 4 is a side elevational view, of the bracelet fastening tool, as viewed from the top;

FIG. 5 is a bottom plan view of the bracelet fastening tool;

FIG. 6 is a top plan view of the bracelet fastening tool;

FIG. 7 is an end view of the bracelet fastening tool as viewed from the rear; and,

FIG. 8 is an end view of the bracelet fastening tool as viewed from the front.

The broken lines composed of short, regular dashes illustrate features of the bracelet fastening device that form no part of the claim, while the long dash-dot-long dash oval perimeter line indicates a boundary within which no subject matter is claimed.

1 Claim, 3 Drawing Sheets
